OTHER PUBLICATIONS

A flyer entitled "A Convenient and Gentle Approach to Aural Examination" published and distributed prior to Jun. 1996. Flyer discloses designs of three plastic curettes sold by Bionix prior to Jun. 1996.

A Miltex catalog page (p. 274) showing steel curettes sold prior to Jun. 1996. The catalog page was also published and distributed prior to Jun. 1996.

Primary Examiner—Ian Simmons

(74) Attorney, Agent, or Firm—Emch, Schaffer, Schaub & Porcello Co., L.P.A.

(57) **CLAIM**

The ornamental design for a curette tip, as shown and described.

DESCRIPTION

FIG. 1 is a top view of a curette tip according to the present design;

FIG. 2 is a side elevational view of the left side of the invention; the right side is a mirror image of this figure;

FIG. 3 is a bottom view of the invention;

FIG. 4 is an end view of the left end of the invention; and

FIG. 5 is an end view of the right end of the curette; and,

FIG. 6 is perspective view of the tip region.
